UNITED STATES PATENT OFFICE.

JOHN E. ALDEN, OF LAKE GEORGE, NEW YORK.

COMBINED TABLE AND SOFA.

SPECIFICATION forming part of Letters Patent No. 378,995, dated March 6, 1888.

Application filed June 16, 1887. Serial No. 241,525. (No model.)

To all whom it may concern:

Be it known that I, JOHN E. ALDEN, of Lake George, in the county of Warren and State of New York, have invented a new and Improved Combined Table and Sofa, of which the following is a full, clear, and exact description.

My invention relates to a piece of furniture adapted for use either as a table or sofa, and has for its object to provide an inexpensive and self-contained structure of this class, which may be easily and quickly set up to serve either of its intended purposes.

The invention consists in certain novel features of construction and combinations of parts of the table and sofa, all as hereinafter described and claimed.

Reference is to be had to the accompanying drawings, forming a part of this specification, in which similar letters of reference indicate corresponding parts in all the figures.

Figure 1 is a plan view of my improvement adjusted as a table. Fig. 2 is a vertical sectional side elevation thereof, taken on the line xx , Fig. 1, with the sofa fixtures removed. Fig. 3 is a transverse sectional elevation taken on the line yy , Fig. 2. Fig. 4 is a sectional side view of the table in inverted position, with the unfolded legs partly broken away and the sofa fixtures packed away in the body or frame of the table. Fig. 5 is a side view of the piece of furniture adjusted as a sofa and partly broken away. Fig. 6 is a perspective view of parts of the table frame and top as when adjusted prior to inverting the table to form the sofa; and Fig. 7 is a plan view of the head portion of the sofa and the end of the table-frame, with parts broken away.

The table-top A is formed of a main or central portion, a , which is fixed to the opposite sides b of the table-frame B, and two opposite end parts, a' , which have lugs a^2 fitting into notches or recesses in the ends b' of the frame. Pins a^3 , passed through the sides b into the ends b' and through the lugs a^2 , form pivots on which the ends a' of the table-top may be swung up at right angles with the table-frame to form legs for the sofa, as hereinafter more fully described. I prefer to shape the meeting edges of the parts a a' of the table-top on an elliptical curve at their central parts, as shown in Fig. 1 of the

drawings. Metal bars or plates C, which are pivoted on pins c within notches at the inner faces of the legs a' , pass at their free ends into recesses c' , which are formed in the sides b of the table-frame. The bars have holes c^2 at or near their free ends, and into which outbent studs d at the ends of short arms of elbow-levers D D are adapted to lock to secure the legs a' in open position. These levers D D are pivoted at their angles at d' to the table-frame B, and the long arms of the levers range inward and slightly overlap each other, and where they overlap they are connected loosely by a pin, d^2 . A spring, E, expanding between the end of the table-frame and the ends of the levers at d' , normally forces the lever-studs d against the bars C and causes the studs to automatically lock into the bar-holes c^2 as the sofa-legs a' are fully raised. To lower the legs the levers D will be pressed inward next the spring to withdraw the studs d from the bars, and the legs may then be folded down to form parts of the table-top. The recesses c' are preferably made with a marginal recess or rabbet, into which a thin board or plate, c^3 , is fastened by screws or pins to form a cover to the sofa-leg bar C and make the outer wall of the bar-recess. The table-top A and its frame B are made preferably of inch stuff, and to the ends b' of the frame, which are made one inch narrower than the frame sides b , blocks F are hinged, thus making the ends of the table-frame, with the blocks F, of the same width as the sides of the frame, and allowing the blocks F to be turned over outward or downward when the table-frame is inverted to place the sofa-top onto it, as hereinafter more fully explained.

The table-legs G are pivoted by pins g to the sides b of the table-frame B, and the tops of the legs are below the table-top A a distance sufficient to allow the levers D to work below the table-top in adjusting the sofa-legs a' , as above explained. When the legs G are unfolded, their outer sides rest against the ends b' of the table-frame, and the opposite legs, forming a pair at each end of the table, are connected by two boards, H H, which are so fixed to the legs as to provide between said boards a space of about an inch, and in which is fitted a series of leg-locking devices, next described. A lever, I, is pivoted at i between

the leg-boards H H about at their center, and to opposite ends of the lever are pivotally connected the inner ends of two bent bars, J J, the outer ends of which are adapted to lock 5 into holes j, made in the sides of the table-frame. A spring, K, which is fixed to one of the pairs of table-legs G, acts normally against the lever I to project the locking-bars J into the frame-holes j when the legs are swung upward from their position within the frame B (shown in dotted lines in Fig. 5 of the drawings) to the position to support the table-top, and shown in Fig. 2 of the drawings. The legs G will thus be securely locked by the bars 10 J J to give the table quite as firm support on its legs as if the legs were made fast to the frame. To unlock the legs G it is only necessary to press the lever I against the tension of the spring K, which will withdraw the bolt-bars J from the sides of the table-frame, when each pair of legs G G, with their connected boards H, may be folded down into the inverted frame when the piece of furniture is to be adjusted as a sofa, as hereinafter more 15 fully explained.

The opposite sides b b of the table-frame are provided with opposite grooves or notches l, into which cross-bars L L may be slipped at their ends to give support within the table-frame to the folded bottom and head-piece and the folded back of the sofa when the table is in use. The sofa bottom and head-piece consists of a board or plate, M, onto which upholstery m is fastened, a board or plate, N, to 30 which upholstery n is attached, and which is hinged at n' to one end of the board M, and a head-piece board or plate, O, having upholstery o, and which is hinged at m' to the other end of the board M. When the legs G are 35 folded down within the inverted table-frame, which then has support upon the sofa-legs a' a', as shown in Fig. 5 of the drawings, and when the end blocks, F F, are thrown over outward, the boards M N may be laid upon the 40 ends b' b' of the table-frame, and the boards will lie snugly between the frame-sides b b to prevent sidewise displacement of the sofa-top from the table-frame, and allowing a person to recline confidently and comfortably 45 upon the sofa. Next the hinge-joint n' the sofa-bottom boards are supported at each side of the table-frame by elastic catches P, which are secured at one end to the frame sides b, and have upper shoulders or flanges which 50 normally spring outward to support the sofa-bottom. The sides b are recessed to allow these catches P to be pressed back flush with the faces of the sides when the legs G are to be folded into the table-frame, or when the 55 sofa fixtures are to be stowed away in the frame.

The back of the sofa consists of two boards, R S, which are provided, respectively, with suitable upholstery, r s, and are hinged together at the upper edge at r', so as to fold over upon 60 each other edgewise and into nearly rectangular form, as indicated by the full and dotted lines in Fig. 5 of the drawings, and to be of

proper size to fit upon the folded part M m of the sofa-bottom within the table-frame. The back-boards R S are each provided with a series of pins, T, which, when the back is unfolded and put in position, enter holes t made in the edge of the side b of the table-frame, and thereby securely hold the two back sections of the sofa to the frame. 75

To lock the back to the head-pieces O o of the sofa, I employ a metal catch-plate, U, made in angular form, and provided at one end with a pin or stud, u, which enters the board R of the sofa-back, and at its other end the catch-plate 80 carries a pin or stud, u', which locks into the board O of the sofa head-piece, and whereby the head-piece will be securely held in the inclined position shown in Fig. 5 of the drawings to make a pillow or head-rest for the person lying on the sofa, and whereby, also, the pins T and catch-plate U together prevent end-wise shifting of the entire sofa-top on its supporting table-frame. 85

When the piece of furniture is adjusted as a table, the legs G will be fastened by the lock-bolts J in extended position and the sofa-legs a' a' will lie flat upon the table-frame, as in Figs. 1, 2, and 3 of the drawings. The sofa fixtures will be stowed away in the table-frame with the parts N O folded upon the part M and the folded-back parts R S laid upon the part M, and will be held in place by the applied bar-supports L, which enter the frame-slots l, the expanding pressure or tendency of 95 the sofa bottom and back being ample to hold the bars firmly in place to support the sofa fixtures out of sight beneath the table-top.

When the piece of furniture is to be adjusted as a sofa, the end parts, a' a', of the table-top 105 will first be raised and locked in place by the levers D entering the bars C, as shown in Fig. 6, and the entire structure will be inverted and supported on the legs a', as shown in Fig. 4. The bars L will then be removed and the 110 sofa bottom and back will be taken out of the frame, whereupon the table-legs G will be folded down into the frame and the sofa bottom and head-piece M N O will be unfolded and put in place on the frame, to which the 115 unfolded back R S will then be adjusted, and when the back portion R is locked to the sloping head-piece by the catch-plate U the sofa is ready for use, as will readily be understood. 120

This piece of furniture can be transformed easily from table to sofa and from sofa to table in very little time by persons of ordinary intelligence, and in either adjustment is a strong and serviceable structure.

Having thus described my invention, what I 125 claim as new, and desire to secure by Letters Patent, is—

1. The combination, in a table and sofa, of a frame, table-legs pivoted thereto and adapted to fold within said frame, a top having hinged 130 end parts which when unfolded form legs to the table-frame when inverted, and a sofa-top comprising hinged sections adapted for application to the inverted table-frame to form

a sofa and to be stowed away within the frame, substantially as described, for the purposes set forth.

2. A combined table and sofa constructed substantially as herein shown and described, and consisting of a frame, B, legs G, pivoted thereto, a lever, I, and lock-bars J J, arranged to lock the legs in extended positions, a table-top, A, formed of a part, a, fixed to the frame B, and two hinged end parts, a' a', which when unfolded form legs to the table-frame when inverted, bars C, pivoted to the part a' and having holes c² at their free ends, levers D D, pivoted to the frame and having studs d, adapted to the bar-holes c², to support the parts a', cross-bars L, fitted loosely to the frame B, and sofa fixtures comprising hinged bottom and head parts, M N O, and a hinged back comprising parts R S, having dowel-pins T, adapted to holes in the table-frame, supports P, for the sofa-bottom on the frame B, and a locking device, U, holding the parts R O to each other, and said sofa fixtures adapted for folding and stowage in the table-frame, all substantially as described, for the purposes set forth.

3. In a combined table and sofa, the table made with a frame, B, legs G, hinged to and adapted to fold within the frame, and a top, A, comprising a part, a, fixed to the frame, and two hinged end parts, a' a', which when unfolded form legs on the inverted table-frame for the sofa, substantially as shown and described.

4. In a combined table and sofa, the table made with a frame, B, legs G, hinged to and adapted to fold within the frame, a top, A, formed of a fixed part, a, and two hinged end parts, a' a', combined with bars C C, pivoted to each end part a', and levers D D, having studs d, adapted to lock the bars to hold the parts a' rigid as sofa-legs, substantially as shown and described.

5. In a combined table and sofa, the table made with a frame, B, legs G G, pivoted at each end of the frame, and said legs connected by a cross bar or bars, H, in combination with a lever, I, and locking-bars J J, attached to opposite ends of the lever and adapted to enter holes in the table-frame, substantially as described, for the purposes set forth.

50 6. In a combined table and sofa, the table-frame provided with notches l, combined with a sectional sofa-top fitting within the frame, and removable cross-bars L, adapted to the

frame-notches for retaining the sofa-top in the frame, substantially as herein set forth. 55

7. In a combined table and sofa, the table-frame made with sides b and ends b', narrower than the sides, in combination with a removable sofa formed with a bottom which rests on the ends b' and between the sides b, substantially as described, for the purpose set forth. 60

8. In a combined table and sofa, the table-frame made with sides b and ends b', narrower than the sides, and provided with hinged blocks F, combined with a removable sofa formed with a bottom which rests on the ends b' and between the sides b when the blocks F are unfolded, substantially as described, for the purposes set forth. 65

9. In a combined table and sofa, the table-frame B, formed with sides b, wider than its ends b', and with legs G, adapted to fold within the frame, combined with a removable sofa formed with hinged bottom parts, M N, which rest on the ends b' and between the sides b, and supports P, fixed to the sides near the joint between the parts M N, substantially as described, for the purposes set forth. 7c 75

10. In a combined table and sofa, the table-frame provided with holes t in the lower edge 80 of one side, and having hinged legs G, adapted to fold within the frame, in combination with a removable sofa made with hinged bottom sections, M N, and head-piece O, bottom rests, P, and a hinged back section formed of parts R S, 85 hinged to fold edgewise, and having dowels T, adapted to the frame-holes t, and a latch device holding the parts R O together, substantially as described, for the purposes set forth.

11. In a combined table and sofa, the combination, with the section R of the removable sofa and its head-piece O, of a catch-plate, U, made in angular form and provided with studs u u', locking into the parts R O, substantially as shown and described. 90

12. In a combined table and sofa, the removable sofa formed of bottom sections, M N, hinged together, a head-piece, O, hinged to the part M, a back formed of sections R S, hinged edgewise at r', and provided with dowels T, 95 100 and a latch device, U, holding the parts R O together, substantially as shown and described.

JOHN E. ALDEN.
